Primary Examiner — Clare E Heflin*(74) Attorney, Agent, or Firm* — Michael Best & Friedrich, LLP(57) **CLAIM**

We claim the ornamental design for an illuminating bollard, as shown and described.

DESCRIPTION

FIG. 1 is an upper perspective view of an illuminating bollard showing the new design.

FIG. 2 is a side elevation view of the illuminating bollard shown in FIG. 1.

FIG. 3 is a top plan view of the illuminating bollard shown in FIG. 1; and,

FIG. 4 is a lower perspective view of the illuminating bollard shown in FIG. 1.

The broken lines illustrate portions of the illuminating bollard that form no part of the claimed design.

1 Claim, 4 Drawing Sheets(56)
